ROGER JOHN DENNETT, OF HASTINGS, CALCUTTA, BRITISH INDIA.

FASTENING, SEALING, AND LABELING DEVICE FOR RAILWAY WAGONS OR THE LIKE.

Application filed April 21, 1920. Serial No. 375,562.

To all whom it may concern:

Be it known that I, ROGER JOHN DENNETT, a subject of His Majesty King George V, and whose address is 8 Canal Road, 5 Hastings, Calcutta, British India, proprietor motor garage, have invented Improvements in and Relating to Fastening, Sealing, and Labeling Devices for Railway Wagons or the like, of which the following 10 is a specification.

The object of this invention is to provide an improved fastener and seal which may be used with railway wagons, warehouses, godowns and the like, for fastening 15 doors or openings. The device is applicable to any opening fitted with a hasp and staple fastening, or with a fastening in which a cotter or equivalent is passed through the slots in lugs or their equivalent, and the opening secured by such staple 20 or cotter being fastened or sealed, the fastening device being arranged to project on one or both sides of the staple or cotter or the like so as to prevent said hasp being 25 opened or said cotter being withdrawn while the said device is in place.

The invention consists essentially of a fastening member, adapted to be passed through a hole in a cotter or the like and to 30 engage a head therefor on the further side of the cotter, said engagement being effected either by deforming the projecting end of the member within said head, or by deforming a separate engaging device to 35 take into a notch, slot or hole in the end of said fastening member and to secure the same within said head. Means may be further provided whereby a seal is affixed to the said head in which the end of the fastening member is fastened. This seal may 40 be arranged to be impressed in such a manner as to secure the strings or the like of a label whereby the said head may be distinguished. The seal may be impressed with 45 distinguishing marks or device and may itself form the engaging device.

My invention will be described with reference to the accompanying drawings, in which like numbers of reference apply to 50 like parts throughout, and in which Figures 1 to 7 show sections of different modifications of my fastening and sealing device, Figures 9 to 12 forms of my limpet or other

washer and Figure 8 shows the application of the fastening means to a cotter. 55

In Figures 1, 2, 4 to 6 the left half of the section illustrates the fastening device as it is on being inserted into the hole, and the right half represents the same when the fastening member has been expanded or 60 made to engage the head and is gripped in position and the seal has been applied.

Figure 1 shows one modification of the fastening means wherein the fastening member or stud 1 passes through a hole 2 in a cotter or the like 3, and is made to engage a head 4 on the further side of the cotter. The engagement takes place by the hollow point 5 of the fastening member being expanded by suitable agency to engage 70 said head. A seal of plastic material 6 may be inserted into the projecting cup 7 formed by the head and be gripped in place by the outer edges 8 of said cup being turned over, or the said head may have inturning edges 75 8^A which will engage the plastic seal when it is deformed by pressure. It will be obvious that given a suitable tool the end 5 of the fastening member 1 and the plastic seal may both be dealt with at one operation 80 provided the seal is in the shape of a washer the end 5 being deformed as shown at 5^A and the seal 6 being pressed into place and impressed with suitable characters or marks simultaneously. 85

In the modification shown in Figure 2 the stud or fastening member 1 passes through the hole 2 in the cotter 3. It also passes through the hole in the special head 4^A. A groove 9 is provided in the stud 1^A into which groove a hollow coned washer known as a limpet washer 10 may be expanded, as shown at 11. Upon such limpet washer being pressed down its outer edge comes in contact with the inner surfaces of 95 the head 4^A and the central hole in such washer becomes reduced in diameter causing the edges of such hole to enter the groove 9 in the stud. A seal 12 may then be forced into the head and, being expanded, will be held in position by the inturning edge 8 of such head. The operation which forces on this seal, which may be made of lead or other suitable material, should also impress the code initials of the despatching 100 station upon the outer periphery 12^A of

such seal. One or more holes or slots 13 may be provided in the sides of the head 4^A. Through two such holes the wire or string 14 of a label 15 as shown in Fig. 3 may be 5 passed and tied, twisted or knotted inside the head before the plastic seal is forced into position. Or, alternatively, holes 16 as shown in Fig. 3 may be made in the sides 10 of the lead or other plastic seal 12 itself, and the string or wire 14 of the label attached thereto before the seal is pressed into position which operation securely fastens 15 the label to the seal. To break open the fastening a jig may be used having jaws 18, 20 as shown dotted in Fig. 2, which can grip the bevelled lower edge 19 of the head 4^A; said jig may have a punch 20, as shown dotted in Fig. 2, whereby the central part 25 of the seal and the stud 1 may be forced out, either shearing the flattened limpet washer 11, or deforming the same again into a coned shape. Or the central portion of the seal and the stud may be punched out, the jig holding the cotter only and the 25 punch pressing out a small disc of lead, forming the central part of the seal, and the stud 1.

In some cases there is no need to bevel the lower side of the head, as shown at 19; 30 but on the other hand the head may be shaped as shown in Fig. 3 and actually have a coned convex surface as shown at 21, to make it more difficult to grip said surface by extraneous agency. At the same time the 35 base 22 of such head may be slightly recessed into the cotter as shown at 23. In such cases also the head of the stud 1^B might be recessed or counter-sunk into the cotter as shown at 24 in Fig. 3. When the fastening 40 is broken by punching out the stud and the central disc of the plastic seal 12 the label 15 is still left attached to the head 4^B or to the seal 12, and the outer part 12^A of the seal, which has the code initials of the 45 despatching station impressed thereon, is not defaced. The head with its seal and label thus still remains intact to identify the wagon after the fastening is broken.

By suitable design the limpet washer 10 50 can be made so as to require any convenient predetermined application of force to press it into position, or to break the fastening.

This washer may be of the true limpet shape, as indicated at 10 in Fig. 2, or it may 55 be in the shape of half a hollow ring split on the plane in which the ring lies as shown at 10^A in Fig. 3.

In either case it has been found preferable to take several small cuts 10^B out of the 60 inner periphery of these limpet or ring washers for the purpose of allowing them to expand more easily into the groove 9, and also so that when the washer is sheared through in opening the fastening the different sections of this inner periphery will

shear off in separate parts and come away readily from the groove 9. If these cuts be not made, the central ring sometimes shears off and remains in the groove 9, blocking the same, and is a little difficult to remove.

In order to centre the limpet washer on the stud 1 it is also preferable to provide three or more inwardly projecting ridges or corrugations 10^C on the inside of such washer to grip and centre the same on said stud 75 by the slight extra spring such corrugations, together with the cuts referred to above, give to such washer.

Instead of using limpet, or other, washers, as described above, I may, if I prefer, pass 80 a loop of wire 25 round the stud 16 said loop lying in the groove 26 made for the purpose in the stud as shown in Fig. 4. It would then require only the application of sufficient force to shear or tear through the loop of wire in order to force off the head 4^C. The wire 25 could be made of any suitable size and might be tightened into the groove 26 by twisting the ends together. If preferred, instead of a wire, a ring with a certain 85 amount of spring in it might be used, which could be slipped down the stud 1^C and be sprung into the cavity 26. Said ring might easily be pushed into position; but when once in position would require a very considerable force to cause the head 4^A to pull 90 away from the stud 1.

In Fig. 5 a further modification is shown 95 in which a hole 27 is provided through the stud 1^D, wherein upon the stud and its head 4^A being assembled in position a piece 100 of wire, split pin or its equivalent 28 may be passed through said hole, preventing the withdrawal of the head 4^A until said wire or pin is sheared through.

It will be obvious that in an embodiment 105 as shown in Fig. 2, after the limpet washer is expanded into place, as shown at 11, it will usually be necessary to shear off the inner edge of said washer when breaking 110 open the fastening. To assist in this process the end of the stud may be specially hardened, or said end might be made of special metal so that the edge of the groove 9 will stand up to the work of helping to shear 115 said limpet washer, or other fastening device without damage. For the same purpose the inner edge 29 of the head 4^A might be specially hardened to stand up to this work 120 without damage. If preferred, the head 4^A might itself be made of some cheap material, such as malleable cast iron, and a special steel washer or ring be let into the 125 same to supply this shearing edge 29. A modification used with a limpet washer is shown in Fig. 3. In this the point of the stud beyond the groove 9 is made of reduced diameter, thereby providing a shoulder 30 on which the inner edge of the limpet or other washer 10 or 10^A before deformation 130

will rest. Upon such limpet or other washer being forced down into position as shown at 11 the inner edge will be contracted and engage in the groove 9. In certain modifications the inner surface of the head 4^A may with advantage be coned as shown at 31, with the result that when such head is torn off, this cone surface will again deform the flattened limpet washer and, in pulling the 10 same out of the groove 9, will cause such limpet washer to regain approximately its original conical shape. By such means it may be possible to use these limpet washers again and again, thus reducing the cost of 15 the fastening to a minimum. As a further precaution I may provide a hole 32 in the point of my stud through which hole wires or strings 33 from another portion of the label 15 may be passed. Such wires 33 20 might pass through holes or slots 13 in the sides of the head 4^A, or, if preferred, they might simply pass into the cavity inside the head 4^A or 4^B over the top, in which case, upon the plastic seal being pressed into position, such wires or strings would pass 25 through and be embedded in such seal. A line of perforations 34 might be provided in the label 15, the object being that, when the fastening is broken open, the strings or 30 wires 33 would be torn away with the stud tearing the label off. It will be realized that the strings or wires 33 might, if preferred, be looped round stud or be fastened to a groove in said stud in such a manner as to 35 cause said wires or strings to be pulled away with the stud when the fastening is broken.

A preferred arrangement, however, is that shown in Fig. 3, in which holes 16 are made in the sides 17 or other part of the lead seal 40 and the strings or wires 14 of the label 15 tied to said seal before the same is pressed into position.

Instead of the edges of the head 4^{CA} being turned over as shown at 8 so that they will 45 grip the plastic seal upon the same being expanded in position the cavity in the head may have straight sides as shown in Fig. 4 and the seal 12 be caused to adhere to the point of the stud 1, the point of said stud 50 being suitably grooved or deformed as shown at 35 to form a key for said seal. In a further modification my stud may be provided with a screw thread as shown at 36 in Fig. 6 and the head 4DA be tapped with a corresponding thread, so that after the stud is 55 passed through the cotter 3 the head may be screwed on. A hole 27, through which a wire or split pin might be passed could be provided in said stud to prevent the head 60 4DA from being unscrewed after the seal is placed in position.

In certain positions on a wagon there is often very little room behind the cotter which can be used for the fastening. In 65 such cases a modification such as that shown

in Fig. 6 might be used, in which the cotter 3 has a hole 2 through it, which hole has two notches or grooves 37 capable of passing a T-head 38 of the stud 1^E. The further side of the cotter 3^A is in this case provided 70 with two notches 39, 39 into which the projections 38 of the T-head may enter. The stud can then be passed in from the front of the cotter until the T-head projections 38 are clear of the further side of the cotter; 75 the stud can then be turned through 90° bringing the projections 38 opposite the notches or depressions 39, into which depressions the T-head can sink until the head is flush with the sides of the cotter. 80

Fig. 7 shows a modification of the arrangement whereby the parts may be assembled, the seal and label placed in position and the whole movement for forcing the limpet or other washer into engagement 85 with the groove 9 and for embossing the seal may be performed as one. In this case a special washer 40 may be interposed between the limpet washer 10 or other deformable washer 10^A, said special washer being 90 sufficiently rigid to cause the limpet washer or its equivalent to crush down into place, the space allowed between said special washer 40 and the seal 12 being such that it will be approximately completely filled by 95 said seal when the seal is properly pressed home.

As an alternative the crushable washer 10^A might be provided with knobs or projections 10^D of such a height that they would 100 certainly have to be crushed down when embossing the seal; said knobs 10^D, which preferably would be three or more in number, would make depressions in the lower side 105 of the seal, but given a suitable size and shape of the cavity in the head 4^A, the crushing down and embossing of the seal could be made to collapse the washer 10^A with certainty sufficiently for it to engage the groove 9 securely. 110

Again, by suitable design, and by using a plastic material giving considerable resistance to deformation and suitable shearing resistance, I may avoid the use of limpet washers or their equivalent altogether and merely rely upon the forcing of the plastic material into a groove 9 or 35 in the stud, said groove in such cases possibly being deeper and wider than shown in the drawings so as to provide greater shearing area 115 in the deformed plastic material. In this case also the label may be attached to the seal. 120

In another modification the deformable washer used may have large square ended cuts 125 10^E taken out of its inner periphery leaving a series of inwardly projecting tongues 10^F, which are bent down forming a modified type of limpet washer; the inward projecting tongues being connected together by a ring 130.

10^E which latter part may, if preferred, be flat. Such a type of washer is shown in Fig. 12 in plan and section. The object of such type is to provide a washer which can be very easily flattened down to engage the groove 9; but which will offer considerable resistance to all these tongues 10^F being sheared off.

The lead or other plastic seal may, when used with a washer such as that last described, be fastened to the washer so that the two together may be inserted into position as one piece and the washer receive the necessary amount of deformation and the seal be squeezed into position and receive its required impression all in one operation.

It will generally be found most convenient for practical use to adopt a type in which the seal and the washer are made together or are attached to each other in the factory before being issued to the traffic staff of a railway. The design could easily be such that the label could be fastened to the seal in the manner hereinbefore described and the one operation fasten, seal and securely label the wagon door.

Fig. 8 shows a method in which, by using a curved cotter 41, the difficulty due to there not being sufficient space to get at the fastening may be avoided. In this case the slot 42 in the staple 43 may be made slightly wider than that necessary for a straight cotter, so that a curved cotter may be used after the hasp 44 is passed over the staple 43 and such cotter be fastened in a manner as described above in this specification.

One great advantage which a label secured by two sets of wires or fastenings connected to the different portions of the label has lies in the fact that one set of these wires may be attached to the head 4^A while the other set may be attached to the stud. If through carelessness the limpet washer, split pin or other device which has been used for fastening the stud has been insecurely put in, it might be possible to withdraw this stud and to open the wagon door without breaking the seal. As, however, one set of wires from the label is, or may be, attached to the said stud, the stud could not be withdrawn without breaking such connections. It will also readily be understood that the attachment of these wires to the stud under the seal will prevent the stud being forced out even if originally properly secured, unless at the same time these wires are ruptured and thus show that the fastening has been tampered with. Figs. 9 to 12 illustrate plans and sections of different types which my limpet washer or its equivalent may take. Fig. 9 illustrates a conical type of limpet washer 10. This type may preferably have a series of small cuts 10^B taken out of its inner periphery for the purpose of making the washer more easy to press down. It

may also have a series of inwardly projecting ridges, depressions or corrugations 10^C which reduce the inner diameter of the washer and help to centre the same on the stud 1.

Fig. 10 shows another convenient type of washer 10^A. This may have small cuts 10^B for the purpose above described.

Fig. 11 is another washer similar to that illustrated in Fig. 10 with the exception that it has a series of knobs 10^D, which knobs are adapted to receive the pressure from the closing van through the medium of the seal itself so that this washer is collapsed, engaging the groove 9 in the stud, and the seal is compressed and embossed with the required code initials, all at one operation.

Fig. 12 shows another type of washer in which certain square ended notches 10^E are taken out of the inner periphery leaving inwardly projecting tongues 10^F attached to a solid ring 10^E. These projecting tongues may be bent up at an angle to the ring 10^E so that the inner diameter between the ends of these tongues is sufficiently large for them to be slipped over the point of the stud 1. Washers of this type can easily be collapsed or flattened, in which process these projecting tongues 10^F enter the groove 9 in the stud and hold the same firmly. This type of washer is a very convenient one for use in conjunction with the seal, the washer and the seal being fastened together so that they can be inserted and pressed into position as one piece in one operation.

It will be understood that in closing, fastening devices of a type as hereinbefore described suitable jigs could be used. Said jigs which may have jaws to embrace the cotter or the like and/or to hold the fastening member therein can readily be designed to operate to deform the end of the fastening member inside the head 4, 4^A 4^B or to deform some device such as a limpet or other washer to engage said member inside said head. These jigs may by the same or a subsequent movement press down and/or emboss or impress the seal into said head. Further the same jigs may be so constructed that they will be capable of embracing the said head or if preferred the cotter or the like while a punch, which may be a part of said jig, operates to break open the fastening by punching out the stud, shearing through, breaking or deforming the expanded end of said stud or the limpet washer, deformable washer, ring, soft iron wire, split pin or the like which has been used to fix said stud into the head. The punch can at the same time shear out a disc from the centre of the seal.

Such punch need only be the same diameter as the point of the stud 1 and in use could force out such stud by pressure only, shearing off or breaking away the inner rim.

of the collapsible washer which has engaged the groove 9 of the stud and punching out a very thin disc from the centre of the seal which disc may be less than $\frac{1}{16}$ th inch thick 5 and will be the only portion of the sealing material which need be lost at each operation. When used in this manner the heads 4, 4^A, 4^B still has retained therein the essential part of the seal with the code initials 10 of the despatching station embossed thereon. If a label has been used, fastened to said head or fastened to the plastic material of such seal, such label will still be attached and will give the evidence required as to 15 the identity of the wagon. If on checking the contents of the wagon it is found that it has not been tampered with these heads 4^A with the plastic seal pressed into them may be sent to store for the lead to be extracted 20 by heating or otherwise so as to recover practically the whole of the material used for the seal.

For railway practice, in cases where a label is not attached to the fastening or 25 seal in one of the manners hereinbefore described, I may use a private number stamped on each seal. The seal would be inserted in the cavity arranged for it, with such private member inside against the bottom of such 30 cavity, and thus hidden from view. Before inserting the seal the station master or other railway official closing and sealing the railway wagon would note the number on such sealing pellet and enter the same in the station records. The seal would then be inserted into the cavity with the private number downwards and the stud engaging means 35 be fixed or expanded into place and the seal impressed with the code initials of the despatching station. Such a procedure will be a double safeguard. For example, a wagon 40 might be sealed and stamped with the code initials of a despatching station some hours before despatch; an unauthorized person might 45 get hold of the fastening and sealing devices, destroy the fastening placed on the wagon by the proper authority, rob the wagon and refasten and seal it again. In the ordinary 50 course of events such a robbery would cause considerable trouble in investigation as it would appear that the wagon had been 55 robbed before being sealed. It having been found on a wagon arriving at its destination that it had been robbed, the broken out head with the seal still held in its cavity could be sent to the head office for examination. The seal could be cut out and the 60 private number verified, and valuable information helping to trace the thief perhaps obtained by a careful following up of the clue so given. It will be obvious to any operating official of the railway that there 65 are very great possibilities in this part of my invention. It is quite easy to provide each station with a supply of lead pellets for

seals, each pellet being stamped with a private number and to make the station staff account for each number used.

After once being properly inserted and sealed this private number is hidden from 70 view and can only be found by cutting the parts of the fastening to pieces to extract the lead seal whole.

To facilitate the using of my sealing methods each wagon might be fitted with a 75 small metal pocket or receptacle on each side of the wagon into which the part of the fastening holding the seal might be dropped and in which it might remain while the contents of the wagon were being checked. If 80 the contents were found to be correct such fastenings could be thrown away if damaged, or sent to stores for the lead used for the sealing device to be recovered and used again and again, and for the other parts to 85 be re-issued to the operating staff; if incorrect, the seal or head, seal and label might be sent for investigation.

It will be quite understood that I do not confine myself exactly to the arrangements 90 described or illustrated; but may use suitable modifications of the same. For instance, instead of a limpet washer or a spring ring, I might, if I preferred, use a small spring staple or U-shaped piece of wire 95 which could be slipped into position and sprung into the groove 9 and which would fasten the stud quite securely when the seal had been forced into place. The head of the stud might be counter-sunk or recessed 100 into the cotter in any convenient manner. The under surface 19 of the head 4^A might, if preferred, be provided with a series of shoulders or projections 45 for the purpose of denying the use of a withdrawing jig 105 with fixed jaws. The object being to necessitate that a jig used for breaking open the fastening end which is adapted to do so by gripping and holding the head 4, 4^A must have jaws capable of gripping the 110 underside 19 at predetermined points. These projections or shoulders 45 might determine the gripping points. They, by suitable spacing, might necessitate the use of 115 gripping jaws on the breaking open jig 110 having three or any desired numbers of claws. They might further prevent a jig with fixed jaws being slipped in to grip the surface 19 and would necessitate the use of a 120 jig whose jaws opened to pass said shoulders and closed again to make contact with the surface 19. The shoulder formed on my stud might, if preferred, be slightly undercut or bevelled so as to present a sloping surface into which the inner edge of the limpet washer could more easily be forced when the same is being flattened and expanded into the position in which it secures the stud: such a slope is indicated in Fig. 3. 125

Another modification my invention may 130

take is the provision of a type of bayonet joint between the point of the stud and the special head. In this modification the point of the stud is provided with a hole through which a pin is passed before the stud is passed through the cotter. The hole in the cotter and in the head is slotted and the head also has certain depressions formed in it so that the stud can be pushed through, rotated through a convenient angle and fall into these depressions, or be forced up ramps. Upon the lead seal being forced into position the stud cannot be further rotated to withdraw the same unless either the pin is sheared through or the seal extracted.

In a further modification the inner surface of the special head has a sharp taper, giving only a small clearance between it and the stud. A soft iron wire ring can be forced into such opening and slipped into the groove formed for locking the stud, such stud if necessary being allowed to have a little longitudinal clearance in the cotter for the purpose. The object of this modification is to prevent the soft wire ring being extracted after it is once in position.

I do not confine the use of my invention to doors and windows only, but may use the same for general purposes. For instance a modification of the same might be used for fastening axle box covers.

In a further modification of my invention I use a stud in conjunction with a head and a plastic seal the material of the seal itself being relied upon to give the necessary resistance to the fastening being broken. For this purpose collapsible washers may be embedded in the plastic material forming the seal; or, alternatively, some sort of reinforcement in the shape of a wire mesh or metallic or other suitable skeleton may be embedded in the seal material to give the same alone an increased resistance to deformation or shear. Such sealing material entering the groove 9 or 35 in the stud may be relied on to constitute the fastening means. The plastic seal indicated in Figure 4 may be of this type and be adapted to secure the stud into the head without the help of other agency.

Having now particularly described and

ascertained the nature of my said invention and in what manner the same is to be performed, I declare that what I claim is:

1. A seal of the character specified comprising a stud, a head having one side formed with a centrally arranged opening receiving said stud and the other side of said head being provided with a cavity communicating with said opening and receiving the forward portion of the stud, and a sealing medium received in said cavity and engaging said stud. 55

2. A seal of the character specified comprising a stud, a head having one side formed with a centrally arranged opening receiving said stud and the other side of said head being provided with a cavity communicating with said opening and receiving the forward portion of the stud, a sealing medium received in said cavity and engaging said stud, said cavity being of a greater diameter than the opening in said head. 65

3. A seal of the character specified comprising a stud, a head having one side formed with a centrally arranged opening receiving said stud and the other side of said head being provided with a cavity communicating with said opening and receiving the forward portion of the stud, and a sealing medium received in said cavity and engaging said stud, there being means to engage the stud and hold the same against accidental displacement. 75

4. A seal of the character specified comprising a stud, a head having one side formed with a centrally arranged opening receiving said stud and the other side of said head being provided with a cavity communicating with said opening and receiving the forward portion of the stud, and a sealing medium received in said cavity and engaging said stud, there being means to engage the stud and hold the same against accidental displacement, the exterior of said head 80 being beveled for engagement by a tool. 90

In testimony whereof I hereto affix my signature in presence of a witness, this 25th day of February 1920.

ROGER JOHN DENNETT.

Witness:

A. O. YARROW.
